United States Patent

Des. 235,425
Patented June 17, 1975

235,425

LIST FINDER

Chuzo Mori, Tokyo, Japan, assignor to Carl Manufacturing Company, Ltd., Tokyo, Japan

Filed Feb. 26, 1973, Ser. No. 336,050

Claims priority, application Japan Sept. 6, 1972

Term of patent 14 years

Int. Cl. D19—02

U.S. Cl. D19—76

FIG. 1.

FIG. 3.

FIG. 4.

FIG. 5.

FIG. 2.

FIG. 1 is a perspective view of a list finder showing my new design with its cover having a slightly depressed rectangular area adapted to accommodate an indicia-bearing indexing label therein;

FIG. 2 is a bottom plan view thereof;

FIG. 3 is a left side elevational view thereof, the right side being a mirror image thereof;

FIG. 4 is a front elevational view thereof; and

FIG. 5 is a rear elevational view thereof.

I claim:

The ornamental design for a list finder, substantially as shown and described.
